(57) **CLAIM**

The ornamental design for a unique magnetic eyeglass frame sunglass clip-on device, as shown and described.

DESCRIPTION

FIG. 1 shows a front view of an embodiment of the unique magnetic eyeglass frame sunglass clip-on device;

FIG. 2 shows a back side view of the sunglass clip-on device;

FIG. 3 shows a perspective left side view of the left sunglass clip;

FIG. 4 shows a perspective right side view of the right sunglass clip;

FIG. 5 shows an upper side view of the sunglass clip-on device;

FIG. 6 shows a bottom side view of the sunglass clip-on device;

FIG. 7 shows a perspective front side view the sunglass clip-on device with the magnetic clip detached;

FIG. 8 shows a perspective side view of the right half of the device with the male component of the magnet visible thereof;

FIG. 9 shows a perspective side view of the left half of the device with the female component of the magnet visible thereof; and,

FIG. 10 shows a perspective front side view thereof attached to an eyeglass frame.

This design is a pair of sun-glass lenses having a frameless design with a magnetic center attachment and a pair of clip-on's attached to the boarder of darkened or polarizing lenses. The center magnetic clip between the left and right sunglass lenses are such wherein one side of the magnetic clip is shaped like a male plug and wherein the opposite magnetic clip is shaped like a female plug. The two clips fit together to form unity. The surface outlook of the clip-on device has the characteristics of those of sunglasses, and are reflective and polished.
